4 Claims. (Cl. 41—1)

1

The present invention relates to an improved method of and apparatus for transferring markings to tracings and the like.

One of the aims of the invention is to avoid the arduous time consuming job of hand lettering all legends, bills of material and descriptive data on mechanical drawings, tracings and the like.

Another aim of the invention is to avoid the laborious, monotonous work of putting in by hand all cross-sectioning or surface markings on a drawing or tracing.

In practically every situation in which blueprints, photostats or like reproductions are employed, it is usually desirable that these blueprints or other reproductions shall have legends or other descriptive lettering thereon containing instructions about machining, drilling and finishing the parts, or containing instructions about heat treatment of the parts, or containing instructions about the manner of assembling the parts, or countless other legends too numerous to mention. In most instances the drawing or tracing is too large to get into a typewriter, or it is too inconvenient to do so, and hence the general practice has been to place all of these legends on the original drawing or on the tracing by hand lettering operations. This is one of the most arduous, time consuming jobs in the ordinary drafting office, and adds greatly to the expense of the tracing. Because of the time and expense involved in these hand lettering operations, it frequently happens that insufficient descriptive data is applied to the tracing or that necessary descriptive data is totally omitted from the tracing rather than go to the trouble of putting it in by hand lettering. Also, to minimize hand lettering, lengthy descriptions, bills of material, etc., are frequently typewritten on separate sheets which are intended to be attached to the blueprints, but these often become detached and lost. Furthermore it is not feasible to paste typewritten sheets to a tracing because of wrinkling, different degrees of light transmission, etc.

The principal object of the present invention is to provide an improved method and apparatus which will enable all of these legends and other written data to be typewritten in a typewriter, and this typewritten subject matter then transferred and impressed upon the desired locations on the tracing.

With reference to the matter of transferring cross-sectioning or surface markings to a tracing, it is also well known that to do a reasonably accurate and artistic job of cross-sectioning a large area or numerous small areas is a time consum-

2

ing, painstaking operation. This is aggravated when the cross-sectioning must symbolize concrete, wood, rubber or some material requiring a distinctive sectioning. The same is also true of surface markings where an elevational view of a particular material should be shown with distinctive surface markings to denote that material.

It is a further object of the invention to provide an improved method and apparatus which will enable cross-sectioning or surface markings to be made from master marking tools upon transfer sheets and then transferred to the tracing. This use of a master marking tool or tools insures that the cross-sectioning or surfacing marking will have machine-like uniformity and neatness.

Another object of the invention is to provide an improved pressure tool for making a pressure transfer of markings from a pliable transfer sheet to a surface intended to receive such markings. This tool comprises a multiplicity of spaced points of pressure contact of small surface area which have a rolling motion over the surface of the transfer sheet, the small surface area of each point enabling a relatively high concentration of pressure to be established at each contact point for making a more effective transfer through the transfer sheet. Preferably, these high pressure contact points consist of a series of balls confined within a retainer ring and driven at a relatively high speed of rotation by an electric motor constituting part of the tool. This motor driven pressure tool is used to transfer typewritten subject matter, cross-sectioning, surface markings and any other desired markings to the tracing or the like.

Other objects, features and advantages of the invention will be apparent from the following detail description of certain preferred embodiments of the invention. In the accompanying drawings illustrating such embodiments:

Figure 1 is a fragmentary front view of a typical tracing before certain desired legends or typewritten subject matter has been transferred thereto;

Figure 2 diagrammatically illustrates the first step of typewriting the desired legends or written subject matter upon a transfer sheet in a typewriter so as to form raised carbon-coated characters on the backside of the transfer sheet.

Figure 3 is an elevational view of the back side of this transfer sheet after its removal from the typewriter, showing the raised carbon-coated characters projecting from this back side;

Figure 4 diagrammatically illustrates the next

step of transferring this typewritten subject matter from the transfer sheet to the face of the tracing;

Figure 5 is a view similar to Figure 1 but showing the same tracing after the typewritten subject matter has been transferred thereto;

Figure 6 is an end view of the motor driven transfer head;

Figure 7 is a fragmentary sectional view showing the mounting of the resilient coupling, pressure head and ball race on the end of the motor shaft;

Figure 8 diagrammatically illustrates the step of preparing a transfer sheet for transferring cross-sectioning;

Figure 9 diagrammatically illustrates the next step of transferring this cross-sectioning from the transfer sheet to a tracing; and,

Figure 10 is a fragmentary elevational view of a modified form of roller for making cross section marks.

In Figure 1 I have shown a portion of a conventional shop tracing, designated 10 in its entirety, which may be composed of either tracing paper or tracing cloth. This tracing contains any desired illustration designated 11 in its entirety, the illustration shown depicting a group of magnetic core structures which are to be assembled in a certain relationship of north and south poles. It will be understood that such illustration 11 has been chosen merely for the purpose of illustrating one general type of technical illustration to which any invention has particular application. The block impression 12 in the corner of the tracing is conventional for identifying the manufacturer, the scale of the parts, the date of the drawing, the initials of the draftsman, etc. We shall assume that it is desired to provide an instruction legend or statement associated with this illustration 11 (such legend being indicated at 13 in Figure 5) for the purpose of showing that in the assembly of the illustrated construction all magnet cores are to be assembled with the north and south poles alternating. In the general practice heretofore followed, this legend or data was put in by hand lettering or writing directly on the tracing.

Referring now to Figure 2 illustrating the first step of my improved method, I take a sheet of any suitable paper 14, such as typewriter paper, and a sheet of carbon paper 15, and place them in a typewriter 16 with the carbon sheet 15 in its usual place in back of the typewriter sheet 14, but with the carbon side 15' of this carbon sheet facing forwardly instead of rearwardly, whereby carbon impressions are made directly on the back of the front sheet 14. The platen roller of the typewriter is diagrammatically indicated at 17, and one of the typebars is diagrammatically indicated at 18. A heavy impression is desired in order to give the maximum height of raised characters projecting from the back of the front sheet 14, and, accordingly, it is the preferred practice to remove the conventional typewriter ribbon extending across the front side of the front sheet. However, this is not essential, and the ribbon may be left in place if it is desired to see the typewritten subject matter on the front side of the sheet 14. This front sheet 14, which becomes the transfer sheet or stencil sheet in the next step of the process, may be composed of any suitable grade of paper which will absorb or retain on its back side an adequate or maximum amount of carbon-coating on each of the raised

type impressions made by the typewriter keys. The paper may also have a slight transparency or translucency with advantage, particularly for the purpose of being able to see the illustration 11 on the tracing through this transfer sheet 14 whereby to facilitate bringing the typewritten subject matter 13 into the proper position with respect to the illustration 11. The carbon paper 15 may be any good standard grade of carbon paper, or it may be a special grade treated for extra sensitivity. It is usually advantageous to use all capital letters on the typewriter for greater legibility of the transferred typewritten subject matter. If desired, special typewriters 15 may be employed having auditing type or other large type more comparable to draftsman's lettering, or "Vari-Typer" composing machines or the like may be used. Furthermore, electric typewriters may be employed for obtaining a heavier touch or deeper type impression.

Figure 3 illustrates the reverse side of the transfer sheet 14 after the completion of the typing of the complete legend, indicated in its entirety at 13. This typical legend chosen for illustration reads as follows:

ASSEMBLE MAGNET CORES WITH
NORTH AND SOUTH POLES ALTERNATING.

The reverse impressions of these type characters appear on the reverse side of the transfer sheet 14, as shown in Figure 3. The blow of each type character against the front side of the paper slightly embosses the paper on the reverse side thereof so that each of these reverse type characters is raised from the surface of the sheet. Under average operating conditions, with a moderately heavy touch on a conventional typewriter, these type characters will project approximately .0002" from the surface of the sheet. When using an electric typewriter, set for heavy touch, this height of each raised character can be considerably increased. It will be understood that each of these raised characters receives a coating of carbon directly from the carbon surface 15' of the carbon sheet 15. Thus, the entire legend or descriptive statement 13 projects rearwardly from the transfer sheet 14 in the form of raised carbon-coated type characters, as clearly shown in Figure 3.

The next step of the operation is illustrated in Figure 4. In this step, the tracing 10 is preferably attached to a drafting board or other hard surface, and the transfer sheet 14 is then placed directly on top of the tracing, with the raised carbon-coated type characters in direct contact with the surface of the tracing. The transfer sheet 14 is maneuvered until the legend 13 is in appropriate registration with its intended position alongside of illustration 11. The transfer sheet 14 may then be fastened in this position by thumb tacks or adhesive tape, or it may merely be held pressed against the tracing by the hand. Thereupon, the transferring operation is performed, preferably by the motor driven pressure unit indicated at 22. This motor driven unit comprises a small portable electric motor 23 which is adapted to be operated in a vertical position, as shown, with one end of the motor shaft 24 extending downwardly therefrom. Secured to this shaft is a resilient coupling 25, preferably composed of a cylindrical block of rubber, although this rotating coupling may also consist of a ball and socket joint, or a coil spring. Secured to the lower end of this rotating resilient

coupling is a pressure head 26 having a group of rounded pressure transmitting points 27 projecting downwardly therefrom. In practice, I prefer to make the parts 26 and 21 from a conventional thrust type of ball bearing, the pressure head 26 being identical with or corresponding to one of the thrust races of such a thrust bearing, and the balls 27 being retained within a ball cage or retainer ring 28. This retainer ring is capable of rotation relatively to the rotating pressure head 26, being held to the pressure head in any suitable manner, such as by a central shank 29 extending down from the pressure head 26 and receiving a screw 30 and washer 31 (Figures 6 and 7), or by a riveted connection, whereby the retainer ring 28 can freely revolve relatively to the pressure head 26. In consequence of this relative freedom of rotation, the ball retainer ring 28 and balls 27 will be carried around as a unit at a speed of approximately one-half that of motor speed. Of course, the balls themselves will have rotative speeds within their respective pockets in the retainer ring 28 much higher than motor speed. The result of this construction is that the balls will normally have a high speed rolling contact with the surface of the paper, with very little sliding contact. This is advantageous because it avoids any tendency of the paper to wrinkle or bunch up ahead of the point of pressure contact and also avoids tearing of the paper. The relatively small or theoretical point contact of each ball with the surface of the paper enables highly concentrated pressures to be transmitted through each ball to the paper, but because this small area of pressure contact is inherently a rolling rather than a sliding contact these highly concentrated pressures do not tear the paper. The lateral flexibility of the resilient coupling 25 also insures that the pressure head 26 will remain parallel with the paper, so that all of the balls 27 will exert substantially equal downward pressure on the paper, even though the motor unit be tipped slightly in maneuvering the unit.

With the transfer sheet 14 held in its proper relation over the tracing 10, this motor driven transfer unit 23 is held in the hand and then moved over the top side of the transfer sheet with a back and forth, circular or other suitable motion for causing the rotating balls 27 to exert pressure contact at substantially every point of the area to be transferred. This can be performed rather quickly, even on large areas, because of the high speed of rolling motion of the balls over the paper. The rotating speed is sufficiently high to insure that when the motor unit is moved across the surface of the paper at a normal, comfortable rate of motion, substantially no point on the surface of the paper will be capable of passing from front to rear or rear to front past or through the circle of rotation of the balls 27 without being intersected by at least one of these balls. The electric motor may be provided with a speed regulator indicated at 33 which can be adjusted to vary the speed of the pressure head 26. This speed regulator can be arranged to vary a resistance in the motor circuit, or to vary the speed in any other preferred manner. The motor may be for use only on alternating current or on direct current, or it may be a universal motor for use on both. Higher speed motors running up to 5000 or 6000 R. P. M. may also be employed, particularly if a smaller motor is desired. The motor may be provided with a stop and start control switch adapted to

be actuated by a plunger button 34 projecting from the motor housing, which plunger button can be readily actuated by the finger while holding the motor in the hand in the operation of maneuvering the transfer unit over the surface of the paper. The weight of the electric motor 23 exerts a substantial amount of concentrated pressure on the ball points 27, and this can be augmented to any desired degree by pressing downwardly on the motor. If a greater concentration of pressure is desired, a different size ball retainer 28 having a smaller number of balls 27 may be substituted for the retainer shown.

The result of the foregoing transfer operation is shown in Figure 5. All of the carbon-coated raised type characters projecting from the underside of the transfer sheet 14 have been subjected to the relatively concentrated pressures of the high-speed rotating balls 27, with the result that the carbon-coating of these type characters has been transferred to the front face of the tracing 10. The permanency of the transfer is adequate for all practical purposes because the carbon-coating will remain on the surface of the tracing practically as long as the carbon-coating remains on the carbon copy of a letter typed in a typewriter. It will be understood that the transfer operation may be performed upon tracing paper, tracing cloth or any other medium intended to receive the transferred subject matter. The tracing is now ready for use in the making of blueprints or any other suitable reproductions. Where several legends, shop instructions or bills of material are to be placed at different points over the surface of a tracing, a plurality of these legends, bills of material, or the like can be typed upon different areas of one transfer sheet, and this transfer sheet then shifted to bring the different typed subject matter into proper juxtaposition to the different figures or other areas on the tracing intended to receive that particular subject matter. Blueprints made from tracings having these carbon-coated characters impressed thereon by the above method and apparatus are entirely satisfactory from the standpoint of clarity and sharpness of definition of the typewritten subject matter. In fact, the uniformity of the typewriter characters makes them easier to read than hand lettering.

My invention can also be used to transfer other markings than typewritten characters. For example, it can be used to transfer cross-sectioning to cross-sectional views on a tracing, or it can be used to transfer surface markings or surface grainings to elevational views on a tracing. This is frequently advantageous where a relatively large area or numerous small areas must be cross-sectioned, or where a relatively large surface area must be given surface markings to denote the nature of the material, its grain or other characteristics.

In Figure 8 I have shown one preferred form of marking device which I prefer to use for making cross-section markings on a transfer sheet. This is in the form of a hand operated roller tool 35 having a roller element 36. Formed around the cylindrical surface of this roller element is a series of uniformly spaced diagonal ribs 37 which have a width and spacing corresponding to a desired type of cross-sectioning. These ribs may be formed in the surface of the roll 36 by engraving, milling, casting or in any other suitable manner. The roller element 36 and ribs 37 are preferably composed of steel or other hard material, although this is not essential. In mak-

ing a transfer sheet 14 with such a roller tool, a sheet of carbon paper 15 is first placed on a hard flat surface with the carbon side 15' of this sheet facing upwardly. Thereupon a sheet of transfer paper, preferably corresponding to the previously described transfer sheet 14, is placed over the sheet of carbon paper. The hand roller 35 is then rolled firmly over the top of the transfer sheet with a relatively heavy pressure so as to produce the carbon-coated markings on the back side of the transfer sheet 14 corresponding to the uniformly spaced diagonal ribs 37 on the roller. This transfer sheet 14 is then placed upon the tracing 10, with the cross-sectional markings superposed over the area of the figure adapted to receive the cross-section markings. The width of the strip of cross-sectional markings on the transfer sheet is preferably made sufficiently wide to exceed the width of the part to be cross-sectioned on the tracing. Hence, the transfer of the carbon-coated markings from the transfer sheet to the tracing is confined to the desired width of the structural part appearing on the tracing by the use of masking strips 39 which are preferably placed between the bottom side of the transfer sheet and the top side of the tracing, but which may be placed upon the top side of the transfer sheet so as to confine or indicate the area to be covered by the motor driven transfer unit 23. These masking strips 39 preferably consist of thin strips of paper which merely serve to prevent any of the carbon markings on the back side of the transfer sheet being transferred to areas of the tracing beyond the desired areas. For example, in Figure 9 the space 40 between the two lines 41 drawn on the tracing 10 is intended to receive the cross-sectioning marks 42 (shown at the right of the figure). Accordingly, the masking strips 39 are brought up to register substantially with the lines 41, and are held there by thumb tacks or adhesive tape. Then, the transfer sheet 14 is placed over the masking strips 39 and space 40, with the carbon coated cross-sectional markings disposed over the space 40 at the desired or proper angle thereto. Thereupon, the motor driven transfer tool 22 is moved back and forth over the back side of the transfer sheet 14 to cause the rolling points of pressure contact 27 to transfer the carbon coated cross-sectional markings to the tracing between the masking strips, as indicated at 42 in Figure 9. A varied assortment of roller tools 35 may be provided, one for indicating the conventional cross-sectioning of rubber, another for the conventional cross-sectioning of concrete, another for the cross-sectioning of wood, etc., and other tools may be provided for indicating a conventional surface graining of wood, or the surface markings of concrete, fabric, or any other desired markings. In all of these roller tools, the roller is preferably constructed with hard sharp surface markings, and the tool is used with considerable pressure so as to cause the markings to be projected appreciably from the under side of the transfer sheet, whereby to form raised, carbon-coated markings.

In Figure 10 I have illustrated a modified form of roller tool 35 for indicating cross-sectioning. In this construction, the roller 36 has a convex periphery, so that it is barrel-shaped, and the spacing between the ribs 37 on this roller is relatively wide at the center of the roller and diminishes in width towards each end. This enables the roller to be used for making cross-sec-

tioning marks of practically any desired width of spacing between sectioning lines. The roller is held at the proper angle to present to the back side of the transfer sheet that part of its axial length that has the desired width of spacing between sectioning lines. This means that only a limited portion of the length of the roller is effective in any single rolling stroke to make markings, and hence the path or band width of the markings is relatively narrow, but that is true of most areas to be cross-sectioned on a tracing, i. e. they are relatively narrow in transverse dimension. Also, it is often the practice to place cross-sectioning in relatively narrow bands around the inside of a figure rather than have the cross-sectioning go entirely across the figure.

I have put the invention to extensive experimental test and commercial use with complete success. I have found that a considerable part of this success is attributable to the principle of the transferring operation inherent in the motor driven transfer tool 22. Accordingly, I regard the use of this tool, or its equivalent, as being the preferred method of practicing the invention. However, I do not regard the invention as entirely limited to the use of this tool, because some benefits of the invention can be obtained, or certain features of the invention can be practiced with reasonable satisfaction, when employing a conventional hand roller, instead of the motor driven transfer tool 22, for transferring markings from a transfer sheet to a tracing or to some other surface adapted to receive markings.

While I have illustrated and described what I regard to be the preferred embodiments of my invention, and the preferred manner of carrying the same into effect, nevertheless it will be understood that such are merely exemplary, and that numerous modifications, rearrangements, and new adaptations can be made without departing from the essence of the invention.

I claim:

1. In a transfer tool for transferring markings from a transfer sheet to a receiving surface, the combination of a retainer cage, a plurality of balls having independent rolling motions in said retainer cage and adapted to have their bottom surfaces bear against said transfer sheet, and a pressure head rotatable relatively to said retainer cage and adapted to exert downward pressure against the top surfaces of said balls, said retainer cage maintaining said balls at a substantially constant spacing out of contact with each other.

2. In a power driven transfer tool for transferring markings from a transfer sheet to a receiving surface, the combination of a retainer cage, a plurality of balls having independent rolling motion in pockets in said retainer cage and adapted to have their bottom surfaces bear against said transfer sheet, a pressure head adapted to exert downward pressure against the top surfaces of said balls, a source of power including a rotary shaft for transmitting rotary motion to said pressure head, and a flexible coupling connecting said rotary shaft with said pressure head, said flexible coupling resiliently transmitting torque to said pressure head and permitting lateral movement between said pressure head and said shaft.

3. In a motor driven transfer tool for performing the herein described method of transferring markings from a transfer sheet to a receiving

surface, the combination of a portable electric motor, a resilient coupling connected to the motor shaft, a rotating pressure head driven by said resilient coupling, a ball cage rotatably connected with said pressure head so as to be capable of rotation independently thereof, and balls in said ball cage having their top surfaces engaged by said pressure head, the bottom surfaces of said balls adapted to be pressed downwardly against the back of the transfer sheet and to be driven with a relatively high speed over the transfer sheet by said electric motor, said resilient coupling serving to transmit torque resiliently to said pressure head.

4. In a transfer tool for transferring markings from a transfer sheet to a receiving surface, the combination of an electric motor adapted to be moved over said transfer sheet with the motor shaft disposed substantially vertically, a resilient coupling secured in torque transmitting relation to the lower end of said motor shaft, a rotating pressure head secured to the lower end of said resilient coupling, and a plurality of balls carried by said rotating head adapted to be pressed downwardly in rolling contact against said trans-

fer sheet for performing the transfer operation, said resilient coupling resiliently transmitting all driving torque from said motor shaft to said pressure head.
